10 Claims. (Cl. 260—461)

1

The present invention relates to new and useful organic phosphate compounds and methods of preparing them.

These new compounds are phosphate esters which conform to the general formula

in which R_1 and R_2 are chosen from the group consisting of aliphatic and aromatic hydrocarbon radicals, and R_3 and R_4 are chosen from the group consisting of hydrogen, aliphatic and aromatic hydrocarbon radicals.

In the new compounds the R 's may be the same or different radicals, and when they stand for aliphatic radicals it is to be understood that they represent both the straight chain and branch chain, the saturated and unsaturated, and the cycloaliphatic hydrocarbon radicals. Typical examples of these radicals are methyl, ethyl, n-propyl, isopropyl, n-butyl, isobutyl, sec.-amyl, n-hexyl, 2-ethyl-hexyl, n-octyl, n-decyl, n-dodecyl, oleyl, cetyl, ceryl, allyl, cyclohexyl, phenyl, and naphthyl.

These phosphate esters may be readily prepared by reacting an acid phosphate of the formula

in which R_1 and R_2 have the meaning shown above, with an unsaturated compound of the formula

in which R_3 and R_4 have the meaning shown above.

A typical reaction in which O,O -dimethyl di-thiophosphoric acid is reacted with diethyl maleate to produce S -(1,2-dicarbethoxyethyl) O,O -dimethyl dithiophosphate may be illustrated as follows:

The unsaturated compounds utilized in the present process may be either maleic acid, the

2

acid maleate esters, the neutral maleate esters, or their isomers, fumaric acid, the acid fumarate esters and the neutral fumarate esters. Therefore, it is to be understood that the formula

used in this specification and the appended claims is intended to represent both the maleate and fumarate compounds.

- 10 When one or both of the reactants are solids, the reaction is preferably carried out in the presence of a solvent. Such solvents include the low molecular weight aliphatic monohydric alcohols, the ketones such as, for example, acetone, methyl ethyl ketone, methyl isobutyl ketone, methyl benzyl ketone, cyclohexanone, acetophenone, and the like; aliphatic esters such as ethyl acetate, amyl acetate, 2-ethylhexyl acetate, methyl propionate, methyl butyrate, ethyl butyrate, and isopropyl butyrate; dioxane, benzene, nitrobenzene, chlorobenzene, toluene, xylene, chloroform, carbon tetrachloride, 1,2-dimethoxyethane, and the trialkyl phosphates such as trimethyl phosphate, triethyl phosphate, and triisopropyl phosphate.

15 The reaction is preferably carried out at a temperature within the range of from about 20° to 150° C. However, temperatures outside of this range may be employed depending upon the type of reactants and solvents utilized.

20 The reaction may be accelerated by using an aliphatic tertiary amine catalyst, such as for example triethylamine, triisopropylamine, tri-n-butylamine, tri-2-ethylhexylamine, and the like.

25 The amount of catalyst employed is usually within the range of from 0.2% to 2.0%, based on the total weight of the reactants.

30 An anti-polymerization agent such as hydroquinone may be employed to guard against polymerization of the maleate or fumarate compound.

35 The following examples will further illustrate the invention.

Example 1

- 40 A mixture of 108 g. of O,O -diethyl dithiophosphoric acid, 86 g. of diethyl fumarate, and 0.2 g. of hydroquinone was heated at 65° C. for 24 hours, then allowed to cool to room temperature. The reaction mixture was taken up in 300 cc. of benzene, washed with 10% sodium carbonate solution and with water. The organic layer was dried over anhydrous sodium sulfate, filtered, and concentrated in vacuo. The residue, 55 S -(1,2-dicarbethoxyethyl) O,O -diethyl dithiophosphate, was a colorless liquid, having a re-

refractive index n_{D}^{25} 1.4895, weighing 170 g. (94% yield).

Example 2

72 g. of dimethyl maleate was added in small portions to a mixture of 94.5 g. of O,O-dimethyl dithiophosphoric acid, 1 cc. of triethylamine, and 0.5 g. of hydroquinone. Cooling was applied as needed to keep the temperature of the reaction mixture below 60° C. After the initial exothermic reaction had subsided, the mixture was heated at 65° C. for 16 hours, allowed to cool to room temperature, and dissolved in benzene. The benzene solution was washed with 10% sodium carbonate solution and with water. The organic layer was dried over anhydrous sodium sulfate, filtered, and heated in vacuo to remove the benzene. The residue, S-(1,2-dicarbomethoxyethyl) O,O-dimethyl dithiophosphate, was a clear colorless liquid having a refractive index n_{D}^{25} 1.5080, weighing 138 g. (91% yield.)

Example 3

The procedure of Example 2 was employed using 34.4 g. of diethyl fumarate, 37.8 g. of O,O-dimethyl dithiophosphoric acid, 0.3 cc. of triethylamine, and 0.2 g. of hydroquinone. 50.8 g. (77% yield) of S-(1,2-dicarbethoxyethyl) O,O-dimethyl dithiophosphate was obtained. The product was a colorless liquid having a refractive index n_{D}^{25} 1.4970.

Example 4

The procedure of Example 2 was employed using 40 g. of di-n-propyl maleate, 40 g. of O,O-dimethyl dithiophosphoric acid, 0.5 cc. of triethylamine, and 0.5 g. of hydroquinone. The reaction mixture was heated at 65° C. for a period of 23 hours. 58 g. (81% yield) of S-(1,2-dicarbo-n-propoxyethyl) O,O-dimethyl dithiophosphate was obtained. The product was a colorless liquid having a refractive index n_{D}^{25} 1.4890.

Example 5

The procedure of Example 2 was employed using 40 g. of diisopropyl maleate, 40 g. of O,O-dimethyl dithiophosphoric acid, 0.5 cc. of triethylamine, and 0.2 g. of hydroquinone. The reaction mixture was heated at 65° C. for 24 hours. 63 g. (88% yield) of S-(1,2-dicarbisopropoxyethyl) O,O-dimethyl dithiophosphate was obtained. The product was a clear pink liquid having a refractive index n_{D}^{25} 1.4862.

Example 6

The procedure of Example 2 was employed using 72 g. of dimethyl maleate, 108 g. of O,O-diethyl dithiophosphoric acid, 1 cc. of triethylamine, and 0.2 g. of hydroquinone. The reaction mixture was heated at 65° C. for 24 hours. 155.5 g. (94% yield) of S-(1,2-dicarbomethoxyethyl) O,O-diethyl dithiophosphate was obtained. The product was a colorless liquid having a refractive index n_{D}^{25} 1.4970.

Example 7

The procedure of Example 2 was employed using 86 g. of diethyl fumarate, 111 g. of O,O-diethyl dithiophosphoric acid, 1 cc. of triethylamine, and 0.2 g. of hydroquinone. 165 g. (92% yield) of S-(1,2-dicarbethoxyethyl) O,O-diethyl dithiophosphate was obtained. The product was a colorless liquid having a refractive index n_{D}^{25} 1.4887.

Example 8

A mixture of 24.1 g. of bis(2-chloroethyl) fumarate, 22.3 g. of O,O-diethyl dithiophosphoric acid, 50 cc. of xylene, 0.3 cc. of triethylamine, and 0.2 g. of hydroquinone was heated at 65° C. for a period of 84 hours. The reaction mixture was cooled to room temperature, diluted with 50 cc. of xylene, washed with 5% sodium carbonate solution and with water. The organic layer was dried over Drierite, filtered, and heated in vacuo to remove the xylene. The residue, S-{1,2-bis[carbo(2-chloroethoxy)ethyl]} O,O-diethyl dithiophosphate, was a pale yellow liquid having a refractive index n_{D}^{25} 1.5110 weighing 31.9 g. (75% yield).

Example 9

The procedure of Example 2 was employed using 40 g. of di-n-propyl maleate, 42.7 g. of O,O-diethyl dithiophosphoric acid, 0.5 cc. of triethylamine, and 0.5 g. of hydroquinone. The reaction mixture was heated at 65° C. for 23 hours. 74.5 g. (96% yield) of S-(1,2-dicarbo-n-propoxyethyl) O,O-diethyl dithiophosphate was obtained. The product was a colorless liquid having a refractive index n_{D}^{25} 1.4852.

Example 10

The procedure of Example 2 was employed using 40 g. of diisopropyl maleate, 43.2 g. of O,O-diethyl dithiophosphoric acid, 0.5 cc. of triethylamine, and 0.2 g. of hydroquinone. The reaction mixture was heated at 65° C. for 24 hours. 76 g. (98% yield) of S-(1,2-dicarbisopropoxyethyl) O,O-diethyl dithiophosphate was obtained. The product was a pale yellow liquid having a refractive index n_{D}^{25} 1.4805.

Example 11

39.2 g. of diallyl maleate was added slowly to a mixture of 44.5 g. of O,O-diethyl dithiophosphoric acid, 0.5 cc. of triethylamine, and 0.5 g. of hydroquinone. After a mildly exothermic reaction had subsided, the mixture was heated at 65° C. for 16 hours. The reaction mixture was cooled to room temperature, washed with 5% sodium carbonate solution and with water, dried over Drierite, and filtered to give 31.4 g. of S-(1,2-dicarboxyethyl) O,O-diethyl dithiophosphate, a colorless liquid having a refractive index n_{D}^{25} 1.5000.

Example 12

The procedure of Example 11 was employed using 22.8 g. of di-n-butyl fumarate, 22 g. of O,O-diethyl dithiophosphoric acid, 0.3 cc. of triethylamine, and 0.2 g. of hydroquinone. The reaction mixture was heated at 65° C. for 21 hours. 31 g. (75% yield) of S-(1,2-dicarbo-n-butoxyethyl) O,O-diethyl dithiophosphate was obtained. The product was a colorless liquid having a refractive index n_{D}^{25} 1.4814.

Example 13

The procedure of Example 11 was employed using 22.8 g. of diisobutyl fumarate, 22 g. of O,O-diethyl dithiophosphoric acid, 0.3 cc. of triethylamine, and 0.2 g. of hydroquinone. The reaction mixture was heated at 65° C. for 24 hours. 25.3 g. (61% yield) of S-(1,2-dicarbisobutoxyethyl) O,O-diethyl dithiophosphate was obtained. The product was a colorless liquid having a refractive index n_{D}^{25} 1.4793.

Example 14

A mixture of 68 g. of bis(2-ethylhexyl) maleate, 45.5 g. of O,O-diethyl dithiophosphoric acid, 150 cc. of benzene, and 2 cc. of triethylamine was allowed to stand at room temperature for 35 days. The reaction mixture was then washed with 5% sodium carbonate solution and with water. The organic layer was dried over Drierite, filtered, and concentrated in vacuo, leaving 95 g. (90% yield) of S-[1,2-bis[carb(2-ethylhexyloxy)ethyl] O,O-diethyl dithiophosphate, a pale yellow liquid having a refractive index n_D^{25} 1.4780.

Example 15

The procedure of Example 2 was employed using 45.2 g. of bis(2-butyloctyl) maleate, 22.3 g. of O,O-diethyl dithiophosphoric acid, 0.5 cc. of triethylamine, and 0.2 g. of hydroquinone. 58.1 g. (91% yield) of S-[1,2-bis[carbo(2-butyloctyloxy)ethyl] O,O-diethyl dithiophosphate was obtained. The product was a clear yellow liquid having a refractive index n_D^{25} 1.4755.

Example 16

The procedure of Example 2 was employed using 26.8 g. of diphenyl fumarate, 22.3 g. of O,O-diethyl dithiophosphoric acid, 1 cc. of triethylamine, and 1 g. of hydroquinone. The reaction mixture was heated at 65° C. for a period of 76 hours. 41 g. (90% yield) of S-(1,2-dicarbophenoxyethyl) O,O-diethyl dithiophosphate was obtained. The product was a viscous brown liquid.

Example 17

The procedure of Example 2 was employed using 17.2 g. of diethyl fumarate, 23.5 g. of O,O-diisopropyl dithiophosphoric acid, 0.5 cc. of triethylamine, and 0.5 g. of hydroquinone. The reaction mixture was heated at 65° C. for 18 hours. 34.0 g. (88% yield) of S-(1,2-dicarbethoxyethyl) O,O-diisopropyl dithiophosphate was obtained. The product was a colorless liquid having a refractive index n_D^{25} 1.4811.

Example 18

The procedure of Example 2 was employed using 11.2 g. of diethyl fumarate, 28 g. of O,O-di-n-decyl dithiophosphoric acid, 0.2 cc. of triethylamine, and 0.2 g. of hydroquinone. The reaction mixture was heated at 65° C. for 23 hours. 33.5 g. (88% yield) of S-(1,2-dicarbethoxyethyl) O,O-di-n-decyl dithiophosphate was obtained. The product was a pale yellow liquid having a refractive index n_D^{25} 1.4769.

Example 19

The procedure of Example 14 was employed using 17.2 g. of diethyl fumarate, 32.3 g. of O,O-diphenyl dithiophosphoric acid, 150 cc. of benzene, 0.3 g. of triethylamine, and 0.2 g. of hydroquinone. The reaction mixture was allowed to stand at room temperature for a period of 7 days. 33 g. (83% yield) of S-(1,2-dicarbethoxyethyl) O,O-diphenyl dithiophosphate was obtained. The product was a pale brown liquid having a refractive index n_D^{25} 1.5532.

Example 20

A mixture of mono-2-ethylhexyl maleate (0.50 mol) and O,O-diethyl dithiophosphoric acid (0.52 mol) was heated at 93°-94° C. for 6 hours, and then allowed to stand at room temperature for 16 hours. Titration of a portion of the product

with 0.1 N sodium hydroxide indicated the reaction to be 99% complete. The product was a yellow, viscous liquid.

Example 21

5 A mixture of mono-n-octadecyl maleate (0.20 mol) and O,O-diethyl dithiophosphoric acid (0.21 mol) was heated at 90° C. for 4 hours. Titration of a portion of the product with 0.1 N sodium hydroxide indicated the reaction to be 97% complete. The product was a yellow, viscous liquid.

10 The phosphate esters of the present invention are adapted for various uses, more particularly as insecticides, and in this connection show remarkably low warm-blooded animal toxicity. They are also useful as fungicides, plasticizers, corrosion inhibitors, flotation agents, and petroleum additives.

15 While the invention has been described with particular reference to specific embodiments, it is to be understood that it is not to be limited thereto but is to be construed broadly and restricted solely by the scope of the appended claims.

20 **I claim:**

25 1. Phosphate esters of the general formula

30 in which R₁ and R₂ are chosen from the group consisting of aliphatic hydrocarbon and aromatic hydrocarbon radicals, and R₃ and R₄ are chosen from the group consisting of hydrogen, aliphatic hydrocarbon and aromatic hydrocarbon radicals.

35 2. S-(1,2-dicarbethoxyethyl) O,O-dimethyl dithiophosphate.

3. S-(1,2-dicarbethoxyethyl) O,O-diethyl dithiophosphate.

40 4. S-(1,2-dicarbomethoxyethyl) O,O-dimethyl dithiophosphate.

5. S-(1,2-dicarbomethoxyethyl) O,O-diethyl dithiophosphate.

6. S-(1,2-dicarbophenoxyethyl) O,O-diethyl dithiophosphate.

45 7. A method of preparing a phosphate ester of the general formula

50 in which R₁ and R₂ are chosen from the group consisting of aliphatic hydrocarbon and aromatic hydrocarbon radicals, and R₃ and R₄ are chosen from the group consisting of hydrogen, aliphatic hydrocarbon and aromatic hydrocarbon radicals, which includes the step of reacting an acid phosphate of the general formula

55 65 in which R₁ and R₂ are chosen from the group consisting of aliphatic hydrocarbon and aromatic hydrocarbon radicals, with an unsaturated compound of the general formula

70 in which R₃ and R₄ are chosen from the group consisting of hydrogen, aliphatic hydrocarbon and aromatic hydrocarbon radicals.

75 8. The method of claim 7 in which the reac-

tion is carried out in the presence of an aliphatic tertiary amine catalyst.

9. The method of claim 7 in which the reaction is carried out in the presence of a solvent.

10. The method of claim 7 in which the reaction is carried out at a temperature within the range of from about 20° C. to 150° C.
